UNITED STATES PATENT OFFICE

EXILIAS E. PAQUETTE, OF WOODSTOCK, ONTARIO, CANADA, ASSIGNOR TO SCOTT & WILLIAMS, INCORPORATED, OF NEW YORK, N. Y., A CORPORATION OF MASSACHUSETTS

SPLICING ATTACHMENT FOR CIRCULAR KNITTING MACHINES

Application filed February 6, 1929. Serial No. 337,908.

This invention relates to an attachment for circular knitting machines by which a spliced area of varying width may be formed in successive courses of a fabric.

One object of the invention is to provide an improved variable cam by means of which the extent through which a splicing yarn is added to a course may be varied. Another object is to provide an improved cam mechanism 5 and pattern control therefor by which the width of the spliced portion may be varied gradually through successive courses and in which the cam mechanism may be restored automatically to a condition for creating 10 another similar portion.

The novel features of the attachment are in the construction of a variable cam mechanism which causes the raising and lowering of a splicing yarn finger during each spliced 20 course and varies or holds constant through successive courses the width of the spliced portion according to the dictates of the pattern mechanism by which the cam mechanism is controlled.

25 A preferred embodiment of the invention is described hereinafter and is illustrated in the accompanying five sheets of drawings to which, in the course of the description, reference is made.

30 In the drawings—

Figure 1 is a rear elevation of a seamless hosiery knitting machine having the present attachment applied to it.

Figure 2 is a partial side view of the same 35 machine.

Figure 3 is an end elevation of the cam drum forming part of the present attachment, the movable cam members of the drum being in their extended position forming a 40 full circumference high portion.

Figure 4 is a side elevation of the drum shown in Figure 3 with the parts in the same relative positions.

Figure 5 is a view, partly in section on the 45 line 5—5 of Figure 3 showing the movable members of the cam drum in side by side position, and a part of the drive mechanism therefor.

Figure 6 is a view, in section on the line 50 6—6 of Figure 5 and showing part of the

drive mechanism for the movable members of the cam drum.

Figure 7 is a side elevation of the cam drum as shown in Figures 3 and 4 but taken from the right hand side of Figure 3, showing 55 the side opposite to that shown in Figure 4.

Figure 8 is a diagram of a stocking which may be made on a machine having the present attachment applied to it.

Figure 9 is a diagrammatic development 60 of the cam showing the relatively movable members forming high and low portions, the members being shown in their extended position giving practically a full circumference.

Figure 10 is a similar view showing the 65 movable members in their side by side position giving a maximum low portion.

In the drawings and description the invention is shown and described as it is applied 70 to the well known Scott & Williams type of seamless hosiery machine with revolving needle cylinder but it should be understood that the invention is applicable to many other types of similar hosiery machines.

The machine has the usual needle cylinder 260 revolvably mounted in the bedplate B and yarn fingers such as the splicing yarn finger F mounted above the needle cylinder on a pin 554 on the pivoted latch ring 550. This latch ring is pivoted on a bracket 401 on the bedplate B, as usual. The yarn fingers are adapted to be lifted out of and lowered into operative position by thrust rods 460 controlled by the usual cam lugs 501 on the main pattern drum 120, which is racked around at 75 irregular intervals throughout the making of the stocking by any suitable mechanism, such for instance as is shown in the patent to Robert W. Scott, Number 1,152,850 granted September 7, 1915. The needle cylinder is adapted to reciprocate or rotate, the reciprocating movement being obtained from a segment gear 75 driven by means of a train of gears including a constantly revolving gear 80 and a pitman 70.

The variable cam drum 10 is fixed on a horizontal shaft 12 which is mounted at the back of the knitting machine in spaced brackets 13 and 13^a. The shaft 12 is driven by the engagement of a small pinion 14 with the 85 90 95

continuously revolving gear 60 which drives the segment 75 in the usual manner. The gear ratio is such that the drum 10 turns once for each revolution of the needle cylinder. This cam drum causes the raising and lowering of the splicing yarn finger F by its action upon a lever 15 which is attached at one end to the outer end of the yarn finger F and at its lower end to a reverse motion lever 17 pivoted at 16 on the shaft bracket 18 so that its free end may rest on the cam drum 10. The free end of the lever 17 is extended laterally as at 19 to give a wide bearing surface over the drum.

The yarn finger F being in its yarn feeding position, that is, resting on the throat plate 559, by reason of the main pattern drum's having been turned until there is no cam lug under the thrust rod 460, the extent of each course through which the yarn finger is in that position is determined by the cam drum 10. Thus the main pattern drum, which controls various operations of the machine in a predetermined relation, determines the period in which the yarn finger may be lowered to feeding position; while the rotary cam drum determines the extent of a course through which the splicing yarn is fed thereto during that period.

The variable cam drum 10 (see Figures 3-7) is made up principally of a cylindrical body 20, two cam segments 21 and 22 on its periphery forming together a cam with relatively variable high and low portions, and a mechanism for moving these segments simultaneously in opposite directions about the axis of the drum and for reversing their movements.

Each cam segment is formed of two members, an outer cam piece, e. g. 21^a, which extends about half way around the drum, and an inner ring e. g. 21^b which surrounds the cylindrical body 20. The two inner rings 21^b and 22^b are spaced axially on the cylinder 20 and each is toothed on its inward face over about half of its circumference to form a rack. The cam pieces 21^a and 22^a are wider than the rings and are so secured to the rings by screws 23 that their inward faces have but a very slight clearance. Retaining collars 24 are removably secured to the cylinder 20 by set screws 25 and serve to hold the cam segments from axial movement on the drum.

The cam segments 21, 22 are moved simultaneously in opposite directions about the axis of the drum by a small pinion 26 on the outer end of a spindle 27 which is so mounted on a radial axis that it places the pinion between the two rings 21^b and 22^b and in engagement with the rack teeth of both. The lower end of the spindle 27 rests on a thin hard metal piece 28 at the bottom of a small radial bore 29. A larger radial bore 30 intersects a bore 31 at right angles thereto extending from one end of the cylinder 20 par-

allel to the axis but eccentric to it. The intersection of the two provides a chamber for a worm 32 and wheel 33. The wheel is secured to the radial spindle 27 while the worm is mounted to turn with a short shaft 34 extending through the bore 31 which is parallel to the drum axis. The spindle 27 is supported, above the wheel 33, by an insert 35 which rests in a counterbore 36 of larger diameter than the bore 30 in which the wheel turns. Washers 37 are placed on either side of the wheel between it and the insert 35 on the one side and the bottom of the bore 30 on the other side.

The worm shaft 34 extends beyond the end wall of the cylinder 20 to receive its driving parts. A collar 38 is held on the shaft by a set screw 39 and thus provides an abutment against which there rests a ratchet wheel 40. On the other or outer side of the ratchet is a leather disc 41 and beyond that a collar 42 and the end portion of a spring presser 43, all held in place by the head of a screw 44 that threads into an axial bore in the outer end of the worm shaft. The spring presser 43 is a piece of leaf spring fixed at one end on a post rigid with the drum and slotted at its other end to straddle the screw 44 and to engage the collar 42. The ratchet, the leather disc and the collar are not secured to the shaft positively but normally they turn with it by reason of being pressed against the inner collar 38 which is fixed to the shaft. The worm shaft 34 is held from endwise movement by a small screw 45 which extends from the outside of the cylinder 20 to engage a groove 46 in the shaft.

The ratchet may be turned in either direction and for this purpose two pawls are provided, one for turning the ratchet in one direction and the other for turning it in the opposite direction. One pawl is formed somewhat as a toggle having two parts hinged together, as at 47 in Figures 3 and 4. One part 48 of this pawl is pivoted, at its end away from the joint, on a fixed pin 49 extending from the end of the cylinder at a point remote from the axis thereof. The free end of the other part lies near the ratchet wheel being drawn inward against a fixed guide pin 50 by a spring 51 which is connected between the two parts of the pawl across the joint 47. A spring 52 held at one end to the cylinder 20 and at the other to a projection of the pivoted part 48 beyond the pivot 49, tends to swing the pawl away from the ratchet wheel.

The other pawl similarly is made up of two parts, one of which is pivoted. This latter part is a lever pivoted at a central point on a pin 53 fixed to the end of the cylinder in such a way that one arm 54 of the lever extends out from the drum substantially radially while the other arm 55 lies toward the drum axis. These two arms are spaced axially so that the outward one 54 lies in a plane

spaced from the plane of the hinge 47 of the other pawl. The inward arm 55 is drawn toward a stop pin 56 by a spring 57 and carries a pivot pin 58 for the member 59 which engages the ratchet. This ratchet engaging member 59 is drawn by a spring 61 towards a guide pin 62 extending endwise from the cylinder.

The cam mechanism just described provides a circular cam having members which form a high portion consisting of the cam pieces 21^a and 22^a and a low portion consisting of that much of the exposed portions of the rings 21^b and 22^b which lies between the remote ends of the cam pieces. The ratio between the high and low portions is varied by turning the pinion 26 and thereby causing the cam pieces to move in opposite directions. The low portion may be reduced to zero by moving the cam pieces until they are on opposite sides of the cylinder and form a continuous circumferential high portion. When moved to positions such that the two cam pieces lie side by side with their ends in register one with the other, the maximum low space is created. If the cam pieces are exactly half of the circumference, this maximum low space is a half circumference. It is desirable however to make the cam pieces less than a half circumference in length, thereby enabling the provision of a low space longer than a half circumference. When such is the case, a fixed cam piece is provided on the cylinder 20 in a position alongside of the cam segments where it can bridge the space between the ends of the cam pieces when they are moved from their side by side positions to their extreme positions. In this manner a continuous full-circumference high cam portion may be obtained in one setting and low portion longer than a half circumference may be had by another setting.

To restrain the cam pieces from movement beyond the point at which they give the desired maximum high portion when they are moved thereto from their side by side position, and beyond the side by side position on their return thereto under reverse movement, stops are provided. These consists of pieces of thin metal secured by screws to the drum, the screws extending through elongated holes in the stop pieces so that the stops may be adjusted circumferentially on the drum. One stop 65 is secured to the retaining ring 24 adjacent the cam segment 21 and has an offset portion 66 lying over the ring 21^b in the path of the cam piece 21^a and in such a position that it engages the trailing end of the latter when the cam segments are moved outwardly from their side by side position. The trailing end of the cam piece 21^a may be cut away over part of its width so that the toe of the follower 17 may drop directly onto the drum without striking the stop 66.

The position (see Fig. 9), determined by this

stop gives the maximum high portion and if the stop is properly set it gives a full circumference high portion, the fixed piece bridging the gap between the adjacent ends of the cam pieces 21^a and 22^a when such a bridge piece is provided. In this condition of the cam drum, no splicing yarn is fed to the needles.

The other stop 67 is secured to the cylinder 20 in the space between the cam rings 21^b and 22^b. It has an upturned portion 68 in the path of a pin 69 carried on the side face of the ring 21^b. The stop is set so that the pin strikes it when the cam pieces 21^a and 22^a are in their side by side position providing the maximum low space. This position is the one illustrated in Figure 10.

When further movement of the cam segments is prevented by the stops, the driving mechanism therefore may continue to operate but it is rendered ineffective by the slip clutches 38, 40, 41 which come into play under such conditions.

The manner in which the cam segments are moved outward from and back to their side by side position by the ratchet and its actuating pawls will be understood by considering the effect of a succession of movements of the pivoted member 48 of one pawl and then of the pivoted member 54, 55 of the other pawl. As the member 48 is moved inwardly about its pivot 49 by a striker mechanism to be described, the pawl, guided by the pin 50, engages the ratchet and turns it. The spring 52 returns the pawl to its normal position. The turning of the ratchet normally causes the worm shaft to turn because the friction connection between the ratchet and the inner collar 33 under pressure of the spring 43 and the screw 44 maintains the driving relation. Thus through the worm 32 and wheel 33 the pinion 26 is turned. Depending, of course, upon the direction of the thread on the worm 32, this turning causes either outward or backward movement of the cam segments but it will be assumed here that the turning of the pinion caused by the pawl member 48 is such that it moves the cam segments outward from their side by side position in which the maximum low space is created toward the position forming a full-circumference high cam. The opposite engagement of the pinion with the rack teeth on the two cam rings 21^b and 22^b is the cause, of course, of the opposite movement of the cam segments.

Movement of the other pawl, caused by rocking the arm 54 in a way which is yet to be described, causes the ratchet 40 to turn in the opposite direction since the pawl member 59 moves against the ratchet teeth in the opposite direction from that of the other pawl. The result is a reverse movement of the cam segments or a movement toward their side by side or registering position.

The stops 65 and 67 limit the permissive

movements of the cam segments and prevent further relative movement between them when they have established a predetermined ratio between the high and low portions regardless of whether or not the ratchet continues to be turned in a given direction after the stop has been reached. This is possible because of the friction connection between the ratchet 40, the driven member, and the driving member, the worm shaft 34, affording a capability of slip. When movement of the cam segments is prevented, the ratchet slips on the collar 38 and turns ineffectively.

A mechanism now to be described, operated from the main pattern drum 120, controls the cam mechanism described above by selecting the pawl to be actuated and by determining the duration of the operative and the inoperative period of each pawl and the relation of these periods to the other operations of the machine in knitting the stocking. The selection of the pawl to be operative determines the direction of drive of the reversible mechanism described above for effecting relative movement between the members on the cam drum which form the high and low portions.

It will be recalled from the preceding description that the hinge 47 and pivoted member 48 of one pawl turn in a plane parallel to but spaced from the plane in which the pivoted arm 54 turns, both being secured to the end of the cam drum 10. This permits selective actuation of them by moving a striker into their respective planes in position to engage them as they turn. This striker is a small lug 71 mounted fixedly on a horizontal rod 72 below and inside of the drum shaft 12. The striker rod is supported in the bracket 18 at one end and at the other end in a bushing 73 on the main frame of the machine and it is movable horizontally in these supports. A spring 74 tends to move the rod to the right in Figure 1. This horizontal movement enables the striker 71 to be put in any desired one of its three selective positions, viz, (1) clear of the pawls, (2) in the path of the hinge 47 and the pawl member 48, (3) in the path of the pivoted pawl member 54.

The striker rod 71 is moved from one selective position to another by an arrangement of levers between the rod and a set of cam lugs on the main pattern drum. The rock lever 76 is pivoted at 77 on an inturned extension of the bracket 18 which supports the drum shaft 12 and the striker rod 72. Its lower end carries a pin 78 which extends into the path of a circumferential series of cam lugs on the main pattern drum 12. At the upper end, the rock lever is attached to a set of levers one of which 79 is pivoted on the bracket 18 to rock at right angles to the rock lever 76 and supports two depending members, one secured to the rock lever 76 and the

other 80 resting in a slot in the end of the striker rod, thus constituting a means for transferring the movement of the rock lever, as caused by the cam lugs, into a horizontal movement of the striker rod against the effort of the spring 74.

When the pin 78 rides up on a high lug 81 on the pattern drum 120, the striker is moved furthest to the left, as the machine is viewed in Figure 1, to lie in the path of the pawl 47, 48. In this position the striker engages the pawl 47 once on each revolution of the cam drum 10 and thereby causes the cam segments to move out from their side by side position and to decrease the spliced extent of the courses. When a low cam lug 82 lifts the pin 78, the striker is brought into the path of the pawl arm 54 (as shown by the dotted outline in Figure 4) and the cam segments are moved toward their side by side position, thus increasing the length of the low space formed by the cams 21, 22 and increasing the width of the spliced area through successive courses. When the pin 78 rests on the pattern drum itself, the spring 74 puts the striker clear of the pawls and the ratio between the low and high portions of the cam 21, 22 is unchanged through successive courses.

The high and low cam lugs 81 and 82 are positioned on the main pattern drum 120, as shown in Figure 1, in such relation to the cam lug 501 which controls the yarn finger F through the thrust rod 460, that when the yarn finger is dropped into feeding position by the rod's riding off its lug 501, the low cam lug 82 comes under and lifts the pin 78 and therefore, through the lever arrangement described, puts the pawl actuator or striker 71 in the path of the arm 54 where it will cause the pawl member 59 to drive the ratchet. Such drive, as explained above, moves the cam segments from their outermost position toward their side by side position resulting in a gradual widening of the spliced area 83 through the courses above the heel. It may be assumed for the present that prior to this movement the cam segments were in position forming a full circumference high cam portion.

While the heel pocket 84 is being knit the cam 501 puts the yarn finger out of feeding position. Thereafter when it is returned to permit splicing of the sole 85 of the foot, the ratio between the high and low portions is left unchanged. This may be done either by having the low lug 82 of such length that it drops the pin 78 before reciprocatory knitting is ended or by merely setting the stop 68 at a point to engage the pin 69 on the cam-ring 21^b when the relatively movable members have established the proper ratio of high and low portions for the last spliced course above the heel. Then the pawl 54 may continue to be operated without affecting the ratio and the low lug 82 may end at any convenient 125

point to drop the pin 78 on a subsequent movement of the drum.

The high lug 81 may be at any point on the pattern drum to take advantage of some movement of the latter in controlling operations of the machine in knitting unspliced portions such as the leg portion above the high splice of the next stocking. The high lug may end so as to put the striker in neutral position clear of the pawls before the next high splice is reached or the slip clutch may be relied upon to prevent further movement of the segments after they have established a full circumferential cam and have been halted by the stop 67. In either case, when the tapered high splice 83 is to be made, the low cam 82 comes into play as described above.

It will be appreciated that due to the many demands put upon the main pattern drum 120 in the course of the knitting of one article, and due to the limitations thereby put on the number of moves it can make, it is not an easy matter to add a new series of lugs to control a new attachment in proper relation to the other operations. The present arrangement avoids much of this difficulty by the provision of the slip clutch in the mechanism which varies the cam ratio. It is not necessary to have a movement of the pattern drum at the end of the tapered high splice nor is it necessary to provide a special movement to effect a reversal of the drive mechanism in the cam. To a large extent then this attachment makes it possible to utilize the existing movements of the pattern drum rather than requiring new movements with the possibility of having to reset all of the lugs on the pattern drum to accommodate them.

It is important to note also that the reverse movement of the cam segments restoring the drum to the proper condition for starting a new tapered splice is gradual, extending over several courses, rather than sudden as in known constructions. This is possible because of the single drive mechanism which is reversible. For that reason, it is not necessary to provide any complex additional mechanism to effect the return movement. This cam with its reversible mechanism, as distinguished from cams in which segments move always in one direction around the drum, makes practicable the use of stops limiting the permissive movement of the members forming the high and low cam portions.

The cam mechanism may be controlled in other ways than the one illustrated and it may be varied in its details. I therefore wish to include within the scope of the protection give me all such constructions as come within the fair range of the following claims.

I claim—

1. In a circular knitting machine having needles and yarn fingers including a splicing yarn finger, the combination of a rotary cam

drum having high and low portions for actuating the splicing yarn finger and mechanism for increasing or decreasing the ratio between said portions, together with means for controlling said mechanism selectively to vary said ratio in either direction or to maintain it constant through successive courses in predetermined relation to the operations of the machine.

2. In a circular hosiery knitting machine having needles, yarn fingers including a splicing yarn finger, means for causing said machine to reciprocate during part of an operative cycle to form a heel, and a pattern drum for controlling the splicing yarn finger so that it may be in feeding position for a number of courses above the heel and in the foot, the combination of a rotary cam drum having high and low portions for determining the feeding and idle periods of the splicing yarn finger in said courses and mechanism for increasing or decreasing the ratio between said portions, together with means controlled by said pattern drum for causing said mechanism to vary said ratio to give a tapered splice above the heel, to maintain the width of the splice constant in the foot courses and to vary said ratio in the opposite direction while an unspliced part is being knit.

3. In a circular knitting machine having needles and yarn fingers including a splicing yarn finger, a rotary cam for determining the extent of a course through which splicing yarn is fed thereto, said cam comprising a drum with members thereon forming high and low portions, and a reversible drive mechanism for effecting relative movement between said members to increase and to decrease the ratio between said portions.

4. In a circular knitting machine having needles and yarn fingers including a splicing yarn finger, a rotary cam for determining the extent of a course through which splicing yarn is fed thereto, said cam comprising a drum with members thereon forming high and low portions, and means for effecting gradual relative movement between said members said means causing said members to reverse their directions of movement to increase and to decrease the ratio between said portions.

5. In a circular knitting machine having needles and yarn fingers including a splicing yarn finger, a rotary cam for determining the extent of a course through which splicing yarn is fed thereto, said cam comprising a drum with members thereon forming high and low portions, a ratchet operated mechanism for effecting relative movement between said members, and separate pawls, one for driving the ratchet in one direction and another for driving in the reverse direction.

6. In a circular knitting machine having needles and yarn fingers including a splicing yarn finger, a rotary cam for determining

the extent of a course through which splicing yarn is fed thereto, said cam comprising a drum with members thereon forming high and low portions, a ratchet operated mechanism for effecting relative movement between said members and means for driving the mechanism in opposite directions.

7. In a circular knitting machine having needles and yarn fingers including a splicing yarn finger, a rotary cam for determining the extent of a course through which splicing yarn is fed thereto, said cam comprising a drum with members thereon forming high and low portions, a reversible drive mechanism for effecting relative movement between said members to increase and to decrease the ratio between said portions, and pattern controlled means for determining the direction of drive of said reversible mechanism.

8. In a circular knitting machine having needles and yarn fingers including a splicing yarn finger, a rotary cam for determining the extent of a course through which splicing yarn is fed thereto, said cam comprising a drum with members thereon forming high and low portions, a reversible drive mechanism for effecting relative movement between said cam members to increase and to decrease the ratio between said portions, and pattern controlled means for determining the direction of drive of said reversible mechanism and its operative and inoperative periods.

9. In a circular knitting machine having needles and yarn fingers including a splicing yarn finger, a rotary cam for determining the extent of a course through which splicing yarn is fed thereto, said cam comprising a drum with members thereon forming high and low portions, a drive mechanism for effecting relative movement between said members to vary the ratio between said portions, said mechanism including a means for normally transmitting the driving effort to said cam segments and for reversing the directions of movement of said cam segments but adapted to end the driving relation when said segments establish a predetermined ratio between said portions.

10. In a circular knitting machine having needles and yarn fingers including a splicing yarn finger, a rotary cam for determining the extent of a course through which splicing yarn is fed thereto, said cam comprising a drum with members thereon forming high and low portions, a drive mechanism for effecting relative movement between said members to increase and to decrease the ratio between said portions, said mechanism including a means for normally transmitting the driving effort to said cam segments and for reversing the directions of movement of said cam segments but adapted to end the driving relation when said seg-

ments establish a predetermined ratio between said portions.

11. In a circular knitting machine having needles and yarn fingers including a splicing yarn finger, a rotary cam for determining the extent of a course through which splicing yarn is fed thereto, said cam comprising a drum with members thereon forming high and low portions, a drive mechanism for effecting relative movement between said members to vary the ratio between said portions, stops limiting the permissive extent of such movement and means for ending the driving relation between said mechanism and said members when the limit of permissive movement is reached.

12. In a circular knitting machine having needles and yarn fingers including a splicing yarn finger, a rotary cam for determining the extent of a course through which splicing yarn is fed thereto, said cam comprising a drum with members thereon forming high and low portions, a drive mechanism for effecting relative movement between said members to vary the ratio between said portions, said mechanism including driving and driven members in frictional engagement but capable of slip when such movement is prevented, and means for preventing further relative movement between said members when they establish a predetermined ratio between said portions.

13. In a circular knitting machine having needles and yarn fingers including a splicing yarn finger, a rotary cam for determining the extent of a course through which splicing yarn is fed thereto, said cam comprising a drum with members thereon forming high and low portions, a drive mechanism for effecting relative movement between said members to vary the ratio between said portions, said mechanism including a slip clutch, and means for preventing further relative movement between the said members when they establish a predetermined ratio between said cam portions.

14. In a circular knitting machine having needles and yarn fingers including a splicing yarn finger, a rotary cam for determining the extent of a course through which splicing yarn is fed thereto, said cam comprising a drum with movable members thereon forming high and low portions, a drive mechanism for effecting relative movement between said members to vary the ratio between said portions, separate means for actuating said drive mechanism in opposite directions and pattern controlled means for selectively rendering said actuating means operative.

In testimony whereof I have signed my name to this specification.

EXILIAS E. PAQUETTE.
